UNITED STATES PATENT OFFICE

CHARLES WILLIAM ABREE COMLEY, OF LONDON, ENGLAND, ASSIGNOR TO COMLEY
TICKET REGISTER COMPANY LIMITED, OF LONDON, ENGLAND, A BRITISH
COMPANY

TICKET-PUNCHING APPARATUS

Application filed January 3, 1928. Serial No. 244,232, and in Great Britain January 14, 1927.

This invention is for improvements in or relating to ticket-punching apparatus of the type comprising a punching mechanism, comprising one or more punching elements for punching a ticket to indicate thereon any one of a predetermined set of values, such as currency values, with or without one or more other punching mechanisms, comprising each one or more punching elements, for punching the said ticket to provide thereon one or more additional indications, such as the distance or time for which the ticket is issued, and/or a particular group of a set of groups for which the tickets may be issued.

In ticket-punching apparatus of this type proposed heretofore comprising a plurality of punching mechanisms, wherein counting mechanisms were associated with the punching mechanisms for totalling the value of, and counting the number of, tickets issued, the various punching mechanisms were actuated independently one of another in succession, and feed mechanism for feeding a strip of uncancelled tickets past the punches was also actuated independently of the punching mechanisms, so that the process of issuing a single cancelled ticket involved a series of manipulations which had to be performed in a correct order, whereby the operation of the machine was rendered complicated and occupied a considerable length of time.

This invention has for one of its objects to simplify the construction of apparatus of the type described, and provide an improved machine which can be operated in a more simple manner and more rapidly than heretofore. Other objects are concerned with mechanism for feeding the tickets in strip form through the apparatus, and an improved construction of punch-actuating mechanism. A further important object is to provide that although a single punch is used for cancelling tickets punched to indicate fares of various values, the total of such values shall be added up and registered on a single counting device. Yet another object is to provide further improvements in apparatus of the kind referred to, so as to ensure simplicity and reliability of operation and to provide a machine comprising

ing relatively few parts which can be manufactured at a low cost.

According to an important feature of the invention, there is provided ticket-punching apparatus of the type described, wherein a said punching mechanism comprises a punching element, for example a currency punch, that is movable at will to any of a plurality of situations on the ticket where, when operated, it will designate different values, for example currency values, representing fares, one for each situation, on the ticket that is punched, in combination with a counting device, and connecting means so operatively connecting said punching element with said counting device that at each punching operation of the punching element in any of said situations the counting device will register and totalize the values corresponding to the situations at which the punching element is operated. Such a single currency or fare punch serves the purpose of a plurality thereof used heretofore and contributes greatly to the simplification of construction of the machine by greatly reducing the number of component parts in the apparatus.

The actuating means aforesaid conveniently comprises a single actuating member, for example a manually-operated lever, so that a ticket can be punched in more than one place by a single operation of one actuating member.

The invention further provides ticket-punching apparatus as set forth above, wherein in a said punching mechanism having a single punching element operatively connected by connecting means with a single counting device, characterized in that the said connecting means is in the form of transmission mechanism having a variable ratio of transmission which is automatically adjusted when the punching element is moved from one situation to another.

Other features of the invention relating to specific constructions of the actuating means, operating mechanism, feed mechanism, arresting means, and connecting means aforesaid will be described hereinafter and pointed out in the claims.

The invention is illustrated diagrammati-

cally and by way of example in the accompanying drawings, wherein:—

Figure 1 is a front elevation of ticket-punching apparatus having some features according to the invention, some parts of the apparatus being shown removed and others broken away;

Figure 2 is a vertical section taken on the line 2—2 in Figure 1 as viewed when looking towards one end of the apparatus, and

Figure 3 is a vertical section taken on the line 3—3 in Figure 1 as viewed when looking towards the opposite end of the apparatus;

Figure 4 is an end elevation of the right-hand end of the apparatus as viewed in Figure 1, a part of the cover being shown removed to expose the feed mechanism;

Figure 5 is a view corresponding to Figure 1 but showing only parts of the feed mechanism in a position different from that in which the same parts are shown in Figure 1;

Figure 6 is a front elevation, parts being shown broken away and parts in section on the line 6—6 in Figure 7, illustrating one form of ticket-punching apparatus according to the invention comprising only one currency punch;

Figure 7 is a vertical sectional elevation taken on the bent line 7—7 in Figure 6, and

Figure 8 shows a portion of a ticket strip for use in the apparatus.

Like reference characters designate like or similar parts throughout the several views.

Referring first to Figures 1 to 5, a vertical rectangular metal casing designated generally 10, having two end walls 11, 12, a bottom wall 13, 113, a back wall 14 and an apertured front wall 15 contains the punching mechanisms aforesaid. The back wall 14 constitutes part of a vertical base plate 16 on which are mounted below the casing 10 a pivot-pin 17 for a spool 18 carrying a paper strip 19 constituting tickets in strip form, and to one side of the spool a second pivot-pin 20 for a feed disc 21 having three sprockets 22 for feeding the ticket strip 19 to beneath the punching mechanisms. Two parallel bars 24, 25 spaced apart between the top and bottom of the casing 10 extend between the end walls 11, 12 and lie just behind the front wall 15, and serve as pivoted supports for twelve punch keys 26, six on each of these bars, those on one bar being arranged alternately with those on the other bar.

Three punching mechanisms each comprising one or more punching elements are accommodated in the casing 10 and are referred to hereinafter as the currency, stage and classification punching mechanisms, respectively.

The currency punching mechanism comprises twelve currency punching elements 30 which are movable vertically in twelve holes,

one for each punch, in the bottom of the casing which is made in two superposed parts 13, 113 spaced apart, between which the ticket strip 19 is fed as described herein-after. The lower of these two parts 13 constitutes a die plate, and the upper 113 a guide plate for the punches 30. In order to economize, these punches 30 are arranged in two rows, six in each row, those in one row being staggered in relation to those in the other row; the keys 26 aforesaid are allotted each to one of these punches 30 and may be designated with various currency values corresponding to the value of the fares punched by them. Such designations may be either on the key heads or on the casing.

Mechanism for actuating each punch 30 selected by pressing a key 26 comprises a frame 32 having two end plates 33, 34 and two cross bars, an upper 35 and a lower 26, 85 both of L-section, mounted to reciprocate vertically in said casing, the end members 33, 34 of the frame being guided by pins and slots to slide against the end walls 11, 12 of the casing 10. A universal bar 39 lying parallel with but above the upper L-shaped bar 35 is mounted to rock vertically by means of horizontal arms 40 at its ends pivoted to lugs on the rear of the plates 33, 34. One of these arms 40 (see Figure 3) which tend to rock down under the action of a spring 41, has at its pivoted end an upwardly directed horn 42 arranged to co-operate, for the purpose described herein-after, with a stop 43 in the form of a rod extending between the end walls 11, 12 of the casing 10.

A horizontal rod 45 of circular cross-section secured in the end walls of the casing 10 lies parallel with and behind the L-shaped bar 36. This rod 45 pivotally carries side by side twelve arms 46 constituting rockers, one for each punch 30, and each rocker pivotally carries a spring-controlled tumbler 47 which bears against a curved shoulder on the stem of the key allotted to the punch of its associated rocker, twelve of these tumblers being provided.

If the punches 30 are spring-pressed upwards the rockers 46 may bear on them, but preferably the rockers and punches are interlocked by means of T-heads of the punches engaging in T-recesses in the rockers. The front end of each rocker 46 lies under the lower edge of the bar 25 and is thereby prevented from being unduly lifted to remove the punches from their guide plate 113.

Each tumbler 47 is pivoted to its rocker between the ends of the latter and has a rearwardly-directed arm 48 pulled upwards by a spring 49 attached to the rod 43. The upper end of each tumbler is formed as a hook 250 adapted to lift and snap under the universal bar 39 when its associated key 26 is pressed. In this position of a tumbler 47 (see Figure 2) the lower flange of the upper L-

shaped bar 35 enters into a notch formed in the rear edge of the tumbler above its arm 48. In this position the tumbler and its associated parts are ready for punching operation which is effected by driving said frame 32 downwards as described hereinafter. During this movement the universal bar 39 is kept in engagement with the engaged tumbler owing to the action of the spring 41, whilst the upper L-shaped bar 35 exercises a downward thrust on the punch through the pivotal connection of the tumbler 47 and rocker 46 of the selected punch 30. When the bar 39 is lifted owing to pressure on a key 26 any tumbler 47 that has previously been engaged by the bar will be released.

The stage punching mechanism aforesaid comprises a single stage punching element 50. This stage punch 50 is associated with the lower L-shaped bar 36 and is movable vertically in a horizontally slotted bracket 51 providing a die plate and a guide plate between which the marginal portion of the ticket strip 19 is fed. This bracket 51 is adjustable by means of a screwthread along a screwthreaded spindle 52 that is journaled in the two end walls of the casing 10 and is rotatable by means of a crank handle 53 fast on the spindle outside the casing. By rotating this spindle one complete revolution, which may be indicated by a clicking pawl or the like, the stage punch 50 and its bracket 51 are caused to travel along the spindle 52 to a position for punching the ticket in the correct space corresponding to the stage or time in question. Conveniently one revolution of the spindle traverses the stage punch 50 through unit distance corresponding to the distance between the stages indicated on the tickets. The head of this stage punch has an annular groove which is always in engagement with the lower L-shaped bar 36, so that whenever a currency punch 30 is used the stage punch 50 is also used.

The classification punch mechanism aforesaid is situated close to the end wall 12 and may comprise any number of classification punching elements. As illustrated, the frame 32 comprises a transverse bar 59 arranged to reciprocate towards and away from a row of five classification punches 60, and a slider 61 movable along said bar 59 is arranged to be operatively engaged with one of said classification punches 60 in any position into which it may be adjusted along said bar. These five classification punches may represent, for example, an ordinary ticket, a return ticket, a child's ticket, a special ticket and a workman's ticket, the tickets being marked O, R, C, T, W correspondingly (see Figure 8). Each punch 60 is spring-pressed upwardly and has a head having an annular groove adapted to be engaged by the slider 61 movable along the bar 59 of H-section. A rod 62 mounted in the frame 32 parallel with

the bar 59 prevents the punches 60 from leaving the guide plate 113. Any convenient means may be provided for shifting the slider 61. As illustrated the slider has a lug 610 which lies between the prongs of a forked end of a lever 611 which is pivoted on the casing at 100 and has its other end formed as a handle 612. The forked end of the lever 611 is curved, and coacts with a notched edge of a segmental plate 613 so arranged that when the lever is in one of the notches, the slider 61 is engaged with the corresponding classification punch 60, as indicated by marks on the casing near the handle.

There are thus three punching mechanisms comprising the currency punches 30, the stage punch 50, and the classification punches 60, and at least one punch of each of these punching mechanisms are normally in use and operated simultaneously prior to the feed of a ticket.

The actuating means for reciprocating the frame 32 to punch a ticket and for feeding the ticket strip 19 after each punching operation will now be described. The upper ends of the end plates 33, 34 of the frame 32 are formed as horizontal slots, and the actuating means comprises a shaft 63 that is journaled in the end walls 11, 12 of the casing 10 and carries two cams or eccentrics 64, one in each slot, for vertically reciprocating the frame 32. Outside the casing 10 the cam shaft 63 carries a pinion 65 which meshes with a spur gear 66 that is pivoted on the casing and has a holding pawl 68 for preventing rotation in one direction. The spur gear has on its outer face four pins 69 arranged at the four corners of a square having its centre at the centre of the gear wheel 66. A vertical feed pawl 70 having an upward extension 71 beyond its notch 72 for engaging the pins 69 is operatively connected by a hooked tail-piece 73 to a sliding plate 74 mounted on the base plate 16 below the casing 10. A quarter of a revolution of the spur gear 66 corresponds to one complete revolution of the pinion 65 and cam shaft 63, so that when the feed pawl 70 drives one of said pins 69 downwards through 90° the punches 30, 50, 60 are driven through the ticket to perforate it and returned to their normal position above the perforated ticket which is then free to be ejected from the machine by the feed of a new ticket into register with the punches.

This plate 74 has a feed-arm 740 integral with it and bent at right-angles thereto extending up behind the pawl 70. This pawl 70 is pivoted on the arm 740 by means of a screw 700, and its tail-piece 73 lies under a leaf-spring 741 secured on the plate 74. This arrangement enables the feed-pawl 70 to rock on the arm 740 and engage a pin 69 on the spur-gear 66 immediately the arm 740 is driven downwards as described hereinafter. After the spur-gear 66 has rotated 130

through a small angular distance the pin 69 engaged by the pawl 70 enters also into a notch 747 in the arm 740 which then relieves the pawl 70 of the drive of the spur-gear 66 and the parts driven thereby. Near the middle of the downward stroke of the members 70 and 740 both of them are automatically disengaged from the downwardly-driven pin 69 and during the remainder of the said 10 downward stroke an edge of the extension 71 of the pawl 70 slides against two of the pins 69 and thereby holds them in a position of rest wherein the cam 64 is at the end of its upward stroke, so that the punches 30, 15 50 and 60 are held in their upper position withdrawn from the ticket strip 19. The pawl-and-ratchet mechanism constituted by the feed members 70, 740 and pins 69 form part of the operating mechanism of the 20 punches and is associated with the feed mechanism of the ticket strip 19 as described hereinafter.

The feed disc 21 is situated at the side of the sliding plate 74 remote from the spool 17 25 and its three sprockets 22 are spaced equally apart. The sliding plate 74 is guided by a pin 75 and slot 73 to move towards and away from the casing 10, is notched at one side 77 for the purpose described hereinafter, and 30 pivotally carries at the opposite longer side the lower end of a second feed pawl 78. This pawl has an upward extension 79 beyond its notch 80 for engagement by a spring 800 which normally holds the pawl in its forward 35 position ready for engaging one of three pins 81 of the disc 21 spaced equally apart around the pivot-pin 20. The pawl 78 has a lug 780 which lies at right-angles to the length of the pawl and abuts against a shoulder 781 on the plate 74 in the normal position of the pawl. The disc 21 has a circumference equal 40 to three times the length of one ticket and has a spring-controlled holding pawl 82 for preventing rotation in one direction.

45 A single actuating member in the form of a lever 84 pivoted to rock at 85 on the base plate towards and away from a handle member 86 fixed on the latter is pivotally connected by means of a link 87 to said sliding plate 74. A spring 88 tends to hold the lever 84 rocked away from the handle 86. A full stroke device is so associated with the actuating member 84 that when the latter has been moved from its one end position towards 50 its second end position, it is prevented from returning to its first end position before the completion of its stroke towards the second end position. As illustrated, this full-stroke device comprises a reciprocating member 55 constituted by said sliding plate 74, and a spring-pressed holding pawl 89 arranged to co-operate therewith, which reciprocating member has one or more projections that extend so far towards said pawl 89 and are so 60 arranged in relation to the pawl that at each

end position of the said member, the pawl 89 is free at one end of the projections, whilst in intermediate positions the pawl 89 is swung out of its straight-line or dead-centre position into such engagement with the projections as to permit the plate 74 to move in only one direction and hold it by jamming engagement against movement in the opposite direction. Such a projection may be in the form of a rectangular lug but is preferably constituted by teeth 77, and the holding pawl 89 conveniently lies horizontally at the lower end of the lug or teeth when the plate 74 is in its upper end position, as shown in Figure 1. When the plate 74 is in its upper end position, as shown in Figure 1, its horn 745 having a straight edge serves to prevent the feed disc 21 from rotating, whilst when the plate 74 is in its lower end position, as shown in Figure 5, the straight edge of the upper part of the plate so aligns two of the pins 81 that rotation of the disc 21 is prevented and a ticket is in register with the punching mechanisms. The plate 74 has a notch 746 into which a pin 81 can enter during the rotation of the disc 21.

In order to facilitate putting a new ticket strip 19 in roll form into the machine after one has been used up, the pivot-pin 17 is slidably mounted on the base-plate 13 which carries a channel guide 90. A circular cup-shaped casing 91 carrying the pin 17 at its centre, has at the rear a tongue 92 of U-section 95 slidable into the guide 90 in its longitudinal direction and forming a dovetailed connection therewith. A flanged circular cover plate 93 fits over the casing 91 and encloses the strip 19 wound on the spool 18. The pivot-pin 17 is hollow and is of two diameters 100 internally to provide a shoulder at 94 near the middle. A split-pin 95 having a coned head 96 is fast on the centre of the cover plate 93 and normally holds the cover in position by bearing with its head against the shoulder 105 94. In order to remove the cover, a box key 110 is inserted into the rear end of the pivot-pin 17 after the same has been removed from the base-plate, whereby the two parts of the head 96 are pressed together, so that the cover 93 115 can be withdrawn. An outlet for the ticket strip 19 is provided in the casing 91 at 97, whence it passes over a curved two-part guide plate 970 to the feed disc 21. An arcuate cover plate 98 pivoted at 99 in the base plate 16 is provided for enclosing the strip 19 on the feed disc on its way to a flaring mouth-piece 100 arranged to direct the ticket strip to the die-plate 13.

A tray 105 divided into or provided with compartments 106, one for each currency punch 30 and one for the group of classification punches 60, is preferably removably carried at the bottom of the casing 10 below the die-plate 13, and a receptacle 107 for the 125

5 punchings made by the stage punch 50 is preferably carried by the bracket 51 in which the stage punch is mounted. This stage punch 50 may have an indicator that extends at the rear wall of the casing to the upper end thereof of where graduations may be provided for indicating the position of the stage punch.

10 Any convenient counting mechanism may be provided for counting the fares or other currency values indicated on the tickets by punching them, and for counting the number of tickets issued from the machine. Conveniently, twelve counting devices 110, provided each with a one-way actuating device 111, have the latter operatively connected each by an upwardly-extending spring-controlled bent rod 112 with a tumbler 47, the lower end of each rod 112 engaging under the arm 48 of the associated tumbler. Another counter 15 may be operatively connected in any convenient manner with the frame 32. As this frame is reciprocated once for each ticket that is issued, this additional counter will register the number of tickets issued from the 20 machine. Likewise, counters may be associated with the classification punches, for counting the number of tickets of each group or class issued. These additional counters are not shown in the drawing for the sake of 25 clearness.

30 A portion of a ticket strip 19 suitable for use with the ticket-punching apparatus described above is shown in Figure 8. This ticket has along one side marginal portion a 35 number of currency denominations or fares 115 arranged in two rows, those in one row being staggered in relation to those in the adjacent row, corresponding to the currency punches 30, and at the opposite marginal portion a number of stage or time indications 116, also arranged in two rows, those in one row being staggered in relation to those in the adjacent row. At one end of the ticket is a row of group or class denominations 117, and the 45 same end of the ticket is provided with a serial number. The illustration shows that a special ticket has been issued in return for a penny fare, at stage 1, which indications were provided on the ticket simultaneously by a 50 single operation of the actuating member 84.

55 The operation of the described ticket-punching and ticket-issuing apparatus is as follows:—Assuming that a penny special ticket has been issued on the first stage of a journey and that a sixpenny return ticket is to be issued on the next stage, the spindle 52 will be turned one revolution whereby the stage punch 50 will be adjusted to its second position. The slider 61 of the classification 60 punches 60 will be moved to disengage the “special” punch and engage the “return” punch and the currency key 26 marked “Sixpence” will be depressed, whereby its associated tumbler 47 will be engaged with the 65 universal bar 39, and the tumbler 47 asso-

ciated with the key 26 marked “One penny” disengaged therefrom. It is then only necessary to grip the actuating lever 84, rock it towards the fixed handle 86 and allow it to return under the action of its spring 88 to its normal position when a ticket will be punched in three places and ejected from the apparatus and a new ticket placed in readiness for perforation by the punches. During the first part of the first stroke of this reciprocatory movement of the actuating lever 84 the selected punches 30 and 60 and the punch 50 are driven down and up positively by the downward movement of the feed pawl 70 and feed arm 740, and only after this movement has been completed does the feed pawl 78 operate to rotate the feed drum 21 one third of a revolution and thereby feed a new ticket into position for punching. During this movement of the feed disc 21 the spur gear 66 is held against rotation by the upward extension 71 of the feed pawl 70 and by the holding pawl 68, and at the end of the driving stroke of the actuating lever 84 the feed disc 21 is held by the plate 74 and by the holding pawl 82 against rotation, and the sliding plate 74 is at the end of its downward stroke and released from its holding pawl 89, as shown in Figure 5. Consequently, when the actuating lever 84 is released it returns under the action of its spring 88 into its normal position, the two feed pawls 70, 78 are lifted and the sliding plate 74 is lifted into its upper end position, when the apparatus is ready for a fresh operation with the same punches or a different selection thereof.

55 Referring now to the ticket-punching apparatus shown in Figures 6 and 7, this is similar to that described above with reference to Figures 1 to 5, except that instead of the plurality of currency punches 30 provided in that machine, only a single currency punch 300 is now used. In this modified construction a lever 120 having a slot 121 extending nearly from end to end thereof is fulcrumed at 122 on a fixed part of the end of the casing 10 from which the tickets issue, and has its other end extending upwards towards the opposite end wall of the casing 10, where it is operatively connected to actuating means described hereinafter. A bar 123 having a slot 124 extending nearly from end to end thereof is arranged parallel with the lever 120, and a pin 129 extends slidably through the slots 121, 124. This bar 123 has at its opposite ends two vertical limbs 224, 225 and constitutes part of a Z-shaped member so guided in the casing 10 as to cause the bar 123 to move vertically when it is reciprocated. Conveniently, the limbs 224, 225 are grooved on their outer edges and embrace frame members 126, 127 that carry anti-friction rollers 128 for cooperating with the said limbs. The lever 120, bar 123 and pin 129 constitute part of connecting means in the form of transmission 120 125 130

mechanism operatively connecting the punch 300 with a single counting device 110, the ratio of transmission of which mechanism is automatically adjusted, as described herein-
5 after, when the punch 300 is moved from one situation on the ticket to another.

The pin 129 is carried slidably on a vertical rod 130 that lies in front of the said bar and lever and is movable in the direction of
10 length of the same. Conveniently, the pin 129 is fast on a sleeve 131 surrounding the rod 130 which is of angular section to prevent the sleeve from rotating. Alternatively, a saddle slidable along but non-rotatable on the rod 130 may carry the pin 129
15 which thus constitutes a floating connection of the lever 120 with the bar 123, and when it is moved along the same it varies the ratio of transmission of the rocking motion of the lever to the bar depending on the varying distance of the pin from the fulcrum of the lever.

The single currency punch 300 is movable along the L-shaped bar 35 which is reciprocated once at each punching operation of the apparatus as described above. When the punch 300 is in one position it will punch a ticket indicating one fare, and when in another position it will indicate another fare.
25 A notched bar 132 is fixed in the casing 10 parallel with the L-shaped bars 35, 36, on which notched bar runs a carriage 133 which carries a horizontally-slotted plate 134, 135 for the passage of the ticket strip 19. These
30 parts 134, 135 are similar to the corresponding parts of the bracket 51 of the stage punch 50, and a guide bar 136 for aligning them is provided in engagement with the perforated guide plates of the same. Anti-friction
35 members in the form of rollers 138 may be provided on the carriage 133 for causing it to run smoothly.

Pivoted on the carriage 133 is a detent 139 in the form of a pawl which is pressed upwards by a spring 140 into the notches of the bar 132, so as temporarily to hold the carriage in any position of adjustment according to the position where the punch 300 is to operate. A handle member 141 for shifting the carriage 133 depends from its lower edge and extends through a longitudinal slot 142 to the outside of the casing 10, and a second handle member 143 attached to the pawl extends downwards through the same slot to a situation above the handle member 141. By gripping the two thumb-pieces of the handle members 141, 143 the pawl 139 can be readily disengaged from the notched bar 132 and the carriage can be simultaneously moved to any desired situation along the latter for punching a ticket in a new place to represent a different fare. The carriage is preferably provided with an indicator visible outside the casing 10 for indicating the fare that will be punched at the various sit-

uations thereof. For this purpose the rod 130 may be extended upwards outside the top of the casing 10 where it may be provided with an arrow head movable along a graduated scale on the top of the casing.

Any convenient actuating means may be provided for rocking the lever 120 a predetermined angular distance about its fulcrum 122 at each operation of the punch 50. If desired, the lever 120 which constitutes an actuating member for the counting mechanism, may extend through the end wall 12 of the casing 10 and be connected in any convenient manner with the feed pawl 70 described above.

As the lever 120 actuates, not the punch 300 but only the counter 110, its angular movement may occur during the whole time occupied by punching a ticket, withdrawing the one or more punches from the ticket and feeding a new ticket into register with the one or more punching mechanisms, whereby steady and reliable operation of the counting mechanism is assured.

A vertical toothed rack 145 is fixed on the feed arm 740 by means of a bracket 146 and drives a spur gear 147 which is free to rotate on the shaft 148 of the spur gear 66. This gear wheel 147 constitutes an idler and meshes with a pinion 149 that is journalled in the end wall 12 of the casing. Fast on the same axle as the pinion 149 is a second pinion 150 which meshes with an arcuate toothed rack 151 fast on the adjacent end of the slotted lever 120, this rack 151 being curved about the fulcrum 122 of the lever 120. Consequently, whenever the feed arm 740 is driven downwards the lever 120 is rocked downwardly through a predetermined angle.

The upper end of the limb 125 is formed as a bearing 152 shaped as a horizontal slot in which is freely slidable a pin carried by a lever arm 153 of a toothed segment 154 fulcrumed at 255 on a frame member of the casing 10. The segment 154 meshes with a pinion 155 arranged to drive the counter 110 by means of a one-way device of any convenient construction such that the counter is operated only when the segment 154 swings in one direction. For example, a one-way clutch may be incorporated in the hub of the pinion 155.

If desired, a comb-like member 160 having teeth that gradually increase in length from one end of the comb to the other may be fixed on the frame of the apparatus so as to lie parallel with the lever 120 and to receive the pin 129 in its slots 161 when the lever 120 is rocked downwards. The guide 160 is so mounted that each of its slots is in register with one of the notches of the notched bar 132, the shorter slots being placed at the end of the notched bar where lower currency values are punched. Preferably a spring is

inserted in the driving connection between the feed mechanism and the slotted lever 120 when such a guide 160 is provided. In this case the lower ends of the slots 161 form 5 slots for the downward movement of the pin 129 and ensure that the counter 110 will not be overrun owing to the lever 120 being rocked through too great an angular distance at the several positions of the single 10 currency punch 300. The comb-like guide 15 160 also ensures that the pin 129 shall move rectilinearly when the lever 120 is rocked and relieves the carriage 133 from stresses which would otherwise tend to shift it along the notched bar 132.

The operation of this modified construction will be readily understood from the above. When a ticket is to be issued the punch 300 is placed in the desired position 20 corresponding to the fare to be paid, the lever 84 is rocked towards the handle member 86, reciprocates the feed members 70 and 740 for actuating the punching mechanism, and thereby rocks the slotted lever 120. At each 25 punching operation this lever 120 is rocked through the same angular distance and the slotted bar 123 is thereby reciprocated a distance which varies according to the distance of the floating-pin 129 from the fulcrum 122 30 of the lever 120. The counter 110 is thereby actuated to register an amount depending on the position of the floating-pin 129 which, in turn, depends on the position of the punch 30. The invention thus provides a single 35 punch 300 for indicating different fares and a single counting device 110 for totalizing the value of all such fares designated by the punch 30. The desired mechanism comprises very few parts, can be made very accurately at a low cost, is reliable in operation 40 and results in a greatly simplified ticket-punching apparatus as compared with those known heretofore.

If it is desired to increase the angular movement of the slotted lever 120 multiplying gear may be provided between it and the feed members 70, 740 or similar parts serving for driving it.

Various modifications may be made in the 45 details of construction described above without departing from the invention as defined in the claims.

I claim:

1. In ticket-punching apparatus of the 50 character described, a punching mechanism comprising a punching element that is movable at will to any of a plurality of situations on a ticket where, when operated, it will designate different values, one for each 55 situation on the ticket that is punched, in combination with a counting device and connecting means operatively connecting said punching element with said counting device, which connecting means comprises a counter-operating member, an actuating member ar-

ranged to be moved through a predetermined distance at each operation of the punching element, and a connecting member that adjustably connects said counter-operating member with said actuating member, is adjusted in position by the movement of the punching element from one situation to another, and thereby varies the amount of movement imparted to the counter-operating member by the actuating member during a 70 punching operation according to the situation of the punching element.

2. In ticket-punching apparatus of the character described, a punching mechanism comprising a punching element that is movable at will to any of a plurality of situations on a ticket where, when operated, it will designate different values, one for each situation, on the ticket that is punched, in combination with a counting device and connecting means comprising a bar that is mounted to reciprocate and is arranged to actuate the counting device once during each reciprocation, a lever adapted to be rocked to and fro through a predetermined angular distance at 80 each punching operation, and a floating connecting member that is adjustable along the lever by said punching element and operatively connects the bar with the lever at different distances from its fulcrum according to 85 the situation of the punching element.

3. A combination of parts as set forth in 90 claim 2, wherein the said bar and lever are arranged parallel to one another extending in the direction of movement of the punching element and having each a slot extending in the direction of length of the same, a rod movable with the punching element in its adjustment extends transversely of the said bar and lever and is movable in the direction of 95 length of the latter, and a floating-pin is mounted to slide on said rod and extends through the slots in the bar and lever.

4. In ticket-punching apparatus of the character described, a punching mechanism 100 comprising a punching element that is movable at will to any of a plurality of situations on a ticket where, when operated, it will designate different values, one for each situation, on the ticket that is punched, in 105 combination with a counting device, a notched bar extending in the direction of movement of the punching element along the ticket, a carriage that is operatively connected with the punching element and is movable parallel 110 with said notched bar, a detent carried by said carriage and arranged to engage notches in the notched bar, and transmission mechanism that operatively connects said carriage with said counting device and has a variable 115 ratio of transmission which is automatically changed when said carriage is moved along the notched bar.

5. A combination of parts as set forth in 120 claim 4, wherein a handle member is at- 125

tached to the carriage, and a second handle member is attached to the said detent, which handle members are arranged one close beside the other so as to be operable in unison.

5 6. A combination of parts as set forth in claim 1, wherein guide means is arranged to guide the said connecting member to move rectilinearly in its various positions of adjustment when driven by said actuating member.

10 7. In ticket-punching apparatus of the character described, the combination of a punching mechanism for punching a ticket to indicate any of a predetermined set of 15 values, feed mechanism for feeding tickets into register with said punching mechanism, and actuating means comprising operating mechanism arranged to actuate said punching mechanism and said feed mechanism, 20 which actuating means comprises a pivotally mounted actuating member, and the operative connection between the said operating mechanism and feed mechanism comprises a rectilinearly-guided driven member to which 25 the said actuating member is pivotally connected.

8. In ticket-punching apparatus of the character described, a punching mechanism comprising a punching element that is movable at will to any of a plurality of situations on a ticket where, when operated, it will designate different values, one for each situation, on the ticket that is punched, in combination with a counting device and transmission mechanism that operatively connects said punching element with said counting device and has a variable ratio of transmission which is adapted to be automatically adjusted when said punching element is 30 moved from one situation to another, feed mechanism for feeding a ticket strip constituting a series of tickets to said punching mechanism, and actuating means comprising a pivotally mounted actuating member 35 and an operating mechanism that is arranged to actuate said punching mechanism and said feed mechanism in succession, the operative connection between which operating mechanism and feed mechanism comprises a rectilinearly-guided driven member to which 40 45 50 the said actuating member is operatively connected.

In testimony whereof I affix my signature.

CHARLES WILLIAM ABREE COMLEY.
